BABY BUNTING

Zeev Scharf, 138 Galloway Ave.,
Staten Island, N.Y. 10302

Filed Mar. 22, 1972, Ser. No. 337,230

Term of patent 14 years

Int. Cl. D6—13

U.S. Cl. D92—2 R

FIG. 1 is a side perspective view of a baby bunting showing my new design;

FIG. 2 is a top plan view thereof; and

FIG. 3 is a front elevational view.

I claim:

The ornamental design for a baby bunting, as shown.
